CARTON PARTITION MEANS

William H. Inman, Newark, N. Y., assignor to
Bloomer Bros. Company, Newark, N. Y., a corporation of New York

Application January 26, 1944, Serial No. 519,769

8 Claims. (Cl. 229—28)

This invention relates to carton partition means, or "fillers," for separating a carton into a plurality of compartments, or cells, for receiving articles to be separately contained, such, for example, as eggs, fruit, or other articles of food, articles of fragile construction, and the like, one object of the invention being to provide an improved device of the above character having a more simple, inexpensive and efficient construction.

Another object is to provide such a device made from a one-piece blank of material capable of being easily and quickly erected in condition for insertion in the carton to be partitioned.

Another object is to provide a device of the character described capable of being readily erected and rigidly secured in erected position.

Another object is to provide a filler having a one-piece construction which is efficient in use and capable of being readily and economically manufactured.

A further object is the provision of such a partition device adapted to be stored and transported as a one-piece, flat sheet of material, or in partly folded, compactly collapsed and substantially flat condition, ready for erection and use.

Still a further object is to afford a one-piece, folding filler capable of being repeatedly secured in erected position, and collapsed and erected again, for repeated use, or as conditions may require.

To these and other ends the invention resides in certain improvements and combinations of parts, all as will be hereinafter more fully described, the novel features being pointed out in the claims at the end of the specification.

In the drawings:

Fig. 1 is a plan view of a cardboard blank, cut and scored, ready for folding into erected position, in accordance with the present invention;

Fig. 2 is a plan view of the blank of Fig. 1, partly folded and in compactly collapsed, substantially flat condition for storage and transportation;

Fig. 3 is an enlarged, fragmentary view of parts shown in Fig. 1, for clearer illustration;

Fig. 4 is a fragmentary plan view showing the side wall portions folded upwardly in course of erection;

Fig. 5 is a side elevation of the parts as shown in Fig. 4;

Fig. 6 is a fragmentary plan view showing a further step in the erection of the device;

Fig. 7 is a side elevation of the parts as shown in Fig. 6;

Fig. 8 is a plan view of the device after erection, ready for insertion in a carton indicated in dotted lines;

Fig. 9 is a side elevation as viewed from the right in Fig. 8;

Fig. 10 is a fragmentary side elevation as viewed from the bottom in Fig. 8;

Fig. 11 is an enlarged, sectional plan on the line 11a—11a in Fig. 10;

Fig. 12 is an enlarged view similar to Fig. 9, but with the side walls folded angularly inward;

Fig. 13 is an enlarged, perspective view of the parts as viewed from the left and below in Fig. 11, and

Fig. 14 is a side elevation of the blank folded for collapsing, substantially as shown in Fig. 2.

The invention is herein disclosed, by way of illustration, as embodied in a form particularly adapted for partitioning a 3 x 4 egg carton, to provide the egg receiving cells, comprising various improvements on United States Patent No. 2,140,001, granted December 13, 1938, to Michael Davitt, for a "Box divider."

Referring more particularly to the drawings, the present embodiment of the invention comprises a one-piece blank 20, Fig. 1, of cardboard, or like material, suitable for folding to form an egg carton "filler," the blank being formed with two longitudinal fold lines, indicated generally at 21 and 22, spaced from each other and from the opposite margins of the blank, to divide it substantially into longitudinal thirds, including opposite side wall portions 23 and 24 and a bottom portion 25. Each of the score lines, 21 and 22, comprises portions, as 26, which are scored, or otherwise weakened, to facilitate folding, as well understood in the art, and also other portions, 27, at which the material of the blank is cut completely through, or slitted. Certain of the cut parts 27 coincide with the longitudinal fold lines 26, while at other spaced parts the cuts extend or curve outwardly, as at 28, into the spaces intermediate the longitudinal fold lines 26 and the opposite margins of the blank, as shown, and for a purpose to be presently described. In the present instance, the outwardly curved cuts 28 are arranged in pairs and there are three spaced pairs in the length of the blank.

The blank is also formed at each of the cuts 28 with transversely extending fold lines 29, 30 and 31, formed partly by lines of scoring or weakening, and partly by cuts extending through the material. The lines, 29 and 31, are located at

the opposite ends of the pairs of longitudinal cuts 28, while the transverse lines 30 are located at the centers or between the cuts of the pairs. The side wall portions 23 and 24 remain hingedly connected with the bottom 25 along the lines 21 and 22, between the cuts 28. These side wall portions are alike in construction so that a description of one applies to both.

It will be seen from the above construction that the side wall portions, 23 and 24, may be folded upwardly about the lines 21 and 22 to a vertical position, as shown in Fig. 4, as a preliminary step in the erection of the filler. This is conveniently accomplished by the fingers of one hand at each end of the blank, after which inward pressure at the ends of the blank cause the pairs of side wall portions 23a and 23b and 24a and 24b to buckle outwardly and the bottom portions 25a and 25b to buckle upwardly, as shown in Fig. 6, the pressure being continued until the parts assume the position shown in Fig. 8. It will be noted that the outwardly curved cuts 28 separating these parts provide extended end portions on the parts 25a and 25b which are enclosed between and supported by the outwardly buckled side wall portions, thus rigidly supporting the upwardly buckled bottom portions 25a and 25b in vertical position.

Means are provided for securely holding the outwardly buckled side wall portions in the erected position shown in Fig. 8, in which they also support the vertically buckled bottom portions, such means comprising, preferably, hinged ears 34, produced by cuts formed along the fold lines 31, so that, in folding, the ears separate from the side walls 32 and remain in the plane of the outwardly buckled portions 23b and 24b. Adjacent the base of the ears, the blank material is cut by a transverse slit 35 and by spaced, oppositely curved cuts 36, to form pairs of opposing hinged ears 37. For engagement between these ears 37, the transverse lines 29 include cuts forming tongues 38 lying in the plane of adjacent side wall portions 32, so that as the parts are moved to the erected position described above, tongues 38 are forced through the corresponding slits 35 between the pairs of ears 37. The inserted thickness of the tongues 38 forces the ears to an inclined position, as best shown in Fig. 13, so that a pull tending to withdraw the tongues tends to wedge them more tightly between the ears 37 and thus oppose a substantial frictional resistance acting to securely hold the parts in engagement with each other, but permitting withdrawal of the tongues by a sufficient outward pull on the ends of the blank.

To prevent interference between the ends of the upwardly buckled bottom portions 25a and 25b and the tongues 38, such bottom portions are formed with registering circular openings 39, through which the tongues freely pass for engagement with the hinged ears 37, as described above. The openings 39 are preferably made of sufficient diameter for clearing the tongues 38 in the vertical position normally occupied by the side wall portions in which the outwardly buckled portions have their lower outer ends 40 alined with the bottom 25 and both resting on the bottom of the carton to be partitioned. In erecting the device, however, it may be convenient to raise the side wall portions to an inwardly inclined position as shown in Fig. 12, in which they may even engage each other at their top edges, and the openings 39 are made large enough to clear the tongues 38 in this position also, so that the

tongues are left free for engagement with the ears in any position to which the side walls may be raised during erection.

In the manufacture of the device, the blank 5 may be merely cut and scored, as described, after which it may be readily bent about its fold lines, but it is preferred to initially bend the material by any suitable erecting machine or form, about the transverse score lines, so that the side wall portions are biased for buckling outwardly and the bottom portions for buckling upwardly, to facilitate both the compact collapsing of the blank for storage and transportation, as shown in Figs. 2 and 14, and also the erection of the device for use.

The device may be quickly and easily erected by grasping and pulling its ends in opposite direction to first bring the parts to the position shown in Fig. 1 after which the side walls are 10 folded upwardly, as shown in Figs. 4 and 5. An inward push on the blank ends then causes the side wall portions to buckle outwardly and the bottom portions to buckle upwardly and, as the parts are moved to the fully erected position 15 shown in Fig. 8, the ends of the upwardly buckled bottom portions are engaged and supported between the outwardly buckled side wall portions, and tongues 38 engage between ears 37 and securely hold the parts in erected position, from 20 which the blank may be again collapsed, however, if desired, by an outward pull on the ends of the blank and return of the parts to the position shown in either Fig. 1, or Figs. 2 and 14.

The invention thus provides a one-piece filler 25 device, which is readily and economically manufactured, conveniently disposed for storage and transportation and quickly and easily erected for use, with means for securely but releasably retaining it in erected position ready for insertion 30 in a carton.

It will thus be seen that the invention accomplishes its objects, and while it has been herein disclosed by reference to the details of one particular embodiment, it will be understood that 35 such disclosure is intended in an illustrative rather than a limiting sense, as it is contemplated that various modifications and changes in the construction and arrangement of the parts will readily occur to those skilled in the art, within 40 the spirit of the invention and the scope of the appended claims.

I claim:

1. A carton partition device comprising a blank 45 formed with longitudinal fold lines spaced from each other and from opposite margins of said blank to provide two side portions and an intermediate bottom portion, said blank having cuts therethrough at spaced parts of said fold lines and being formed also with transverse fold lines at the ends and intermediate portions of said cuts 50 to provide opposite side portions adapted to buckle outwardly and bottom portions adapted to buckle upwardly, and cooperating elements on said buckling side and bottom portions arranged for engagement with each other by the erection of said blank, to hold said portions in buckled, cell-forming position.

2. A carbon partition device comprising a blank 55 formed with longitudinal fold lines spaced from each other and from opposite margins of said blank to provide two side portions and an intermediate bottom portion, said blank having cuts therethrough at spaced parts of said fold lines and being formed also with transverse fold lines 60 at the ends and intermediate portions of said cuts to provide opposite side portions adapted to buckle outwardly and bottom portions adapted to buckle upwardly, and cooperating elements on said buckling side and bottom portions arranged for engagement with each other by the erection of said blank, to hold said portions in buckled, cell-forming position.

to provide opposite side portions adapted to buckle outwardly and bottom portions adapted to buckle upwardly, and tongues projecting from and aligned with said side portions, said outwardly buckling side portions having slots formed therein to receive and retain said tongues, respectively, to hold said portions in buckled, cell-forming position.

3. A carton partition device comprising a blank formed with longitudinal fold lines spaced from each other and from opposite margins of said blank to provide two side walls and an intermediate bottom, said blank being cut through at spaced parts of said fold lines by cuts extending outwardly intermediate said longitudinal fold lines and said margins and said blank being formed also at each of said cuts with transversely extending fold lines, the portions of said side walls between said transverse fold lines being buckled outwardly and the portions of said bottom between said transverse fold lines being buckled upwardly and having their ends provided with openings therethrough and enclosed between said outwardly buckled side wall portions, and cooperating elements on opposite sides of said side wall portions for engagement with each other through said end openings for holding said buckled portions in cell-forming position and limiting outward movement of said side walls.

4. A carton partition device comprising a blank formed with longitudinal fold lines spaced from each other and from opposite margins of said blank to provide two side walls and an intermediate bottom, said blank being cut through at spaced parts of said fold lines by cuts extending outwardly intermediate said longitudinal fold lines and said margins and said blank being formed also at each of said cuts with transversely extending fold lines, the portions of said side walls between said transverse fold lines being buckled outwardly and the portions of said bottom between said transverse fold lines being buckled upwardly and having their ends enclosed between said outwardly buckled side wall portions, and cooperating elements at opposite sides of said outwardly buckled side wall portions for engagement with each other to hold said buckled portions in cell-forming position.

5. A carton partition device comprising a blank formed with longitudinal fold lines spaced from each other and from opposite margins of said blank to provide two side walls and an intermediate bottom, said blank being cut through at spaced parts of said fold lines by cuts extending outwardly intermediate said longitudinal fold lines and said margins and said blank being formed also at each of said cuts with transversely extending fold lines, the portions of said side walls between said transverse fold lines being buckled outwardly and the portions of said bottom between said transverse fold lines being buckled upwardly and having their ends enclosed between said outwardly buckled side portions, and tongues projecting from and aligned with said side walls, said outwardly buckled portions of said side walls having slots formed therein to receive and retain said tongues,

respectively, to hold said portions in buckled, cell-forming position.

6. A carton partition device comprising a blank formed with longitudinal fold lines spaced from each other and from opposite margins of said blank to provide two side walls and an intermediate bottom, said blank being cut through at spaced parts of said fold lines by cuts extending outwardly intermediate said longitudinal fold lines and said margins and said blank being formed also at each of said cuts with transversely extending fold lines, the portions of said side walls between said transverse fold lines being buckled outwardly and the portions of said bottom between said transverse fold lines being buckled upwardly and having their ends provided with openings therethrough and enclosed between said outwardly buckled side wall portions, said outwardly buckled side wall portions having slots formed therein, and tongues on said side walls projecting through said openings and interlocked with said slots, to hold said buckled portions in cell-forming position.

7. A carton partition device comprising a one-piece blank formed with longitudinal fold lines spaced from each other and from opposite margins of said blank to provide opposite side walls and an intermediate bottom, said blank being cut through at spaced parts of said fold lines by cuts separating said side walls and bottom, and said blank being formed also at each of said cuts with transversely extending fold lines, the portions of said side walls between said transverse lines being buckled outwardly and the portions of said bottom between said transverse fold lines being buckled upwardly to form article receiving cells, hinged ears formed in pairs by cuts in said outwardly buckled side wall portions with the ears of each pair separated by a cut, and tongues formed on said side walls for releasable engagement between said ears to hold said outwardly buckled portions in cell-forming position.

8. A carton partition device comprising a one-piece blank formed with longitudinal fold lines spaced from each other and from opposite margins of said blank to provide opposite side walls and an intermediate bottom, said blank being cut through at spaced parts of said fold lines by cuts extending outwardly intermediate said longitudinal fold lines and said margins, and said blank being formed also at the ends and center of each of said cuts with transversely extending fold lines, the portions of said side walls at each cut between said transverse lines being buckled outwardly and the corresponding portions of said bottom being buckled upwardly and having their ends provided with openings therethrough and enclosed and supported between said outwardly buckled side wall portions, hinged ears formed in pairs by cuts in said outwardly buckled portions with the ears of each pair separated by a cut, and tongues on said side walls projecting through said openings and frictionally engaged between said ears to hold said buckled portions in cell-forming position.

WILLIAM H. INMAN.
